Application August 25, 1948, Serial No. 46,064

9 Claims. (Cl. 188—97)

1

This invention relates to a hydraulic check unit, and particularly to an improved hydraulic check unit adaptable for checking the movements of the picker stick of the loom. In the copending application of George H. Hufferd, Serial No. 37,950 filed July 9, 1948, and assigned to the assignee of this application, there is disclosed and claimed a hydraulic check unit which is particularly adaptable for checking the movements of the picker stick of a loom. This application constitutes further improvements in the construction of such a hydraulic check unit, and in particular, provides an improved expandable volume reservoir chamber for accommodating quantities of fluid temporarily displaced from the primary cylinder chamber as occurs when the hydraulic medium undergoes thermal expansion or when the hydraulic medium is displaced by the entry of the piston rod into the primary cylinder chamber or as the result of the relative displacement occurring when the piston undergoes rapid movement.

As is well known, the picker stick of a fly shuttle loom, and hence the linkage which controls the movements of such picker stick, are subject to very rapid acceleration in both directions of its movement. When a hydraulic check unit is applied to a picker stick control linkage in the manner described in the above identified pending application of George H. Hufferd, it has been found that the movements of the piston of the check unit throughout those portions of the stroke of a picker stick wherein checking is not desired, such as in the initiation of the power stroke, is so rapid as to temporarily displace an excess of fluid from the cylinder chamber, in which the piston operates, through the throttling apertures into the reservoir chamber. The volume of the cylinder chamber available for containing the hydraulic medium also varies as the piston rod enters and leaves the chamber. After a fly shuttle loom has been in operation over a short period of time, the hydraulic check unit will be subjected to a normal operating temperature of approximately 150° F. Thus, the hydraulic medium will undergo a noticeable increase in volume. It is therefore necessary that the reservoir chamber incorporate some means for permitting the ready accommodation of displaced fluid, yet at the same time prevent the addition of any air to the cylinder chamber of the check unit which would result in the check device becoming unreliable in operation.

Accordingly, it is an object of this invention to provide an improved hydraulic check unit in-

2

corporating an expandable volume reservoir chamber of unusual simplicity and reliability.

Another object of this invention is to provide an improved unitary casing for hydraulic check units which not only defines a primary chamber within which the piston of the check unit operates, but in addition defines a vertically superimposed reservoir chamber in fluid communication with throttling apertures in the primary chamber to receive fluid displaced from the primary chamber and accommodates such fluid by compression of entrapped air at the top portions of the reservoir chamber.

Still another object of this invention is to provide an improved construction of a filling opening for a reservoir chamber of the type having a trapped air space in the top portion thereof, wherein a depending sleeve defines the filling opening and provides a convenient indication of the proper fluid level within the reservoir chamber which will provide the required height of trapped air space.

The specific nature of the invention, as well as other objects and advantages thereof, will become apparent to those skilled in the art from the following detailed description of the annexed sheets of drawings, which, by way of preferred example only, illustrate one specific embodiment of the invention.

30 On the drawings:

Figure 1 is a side elevational view of a picker stick linkage for a loom incorporating a hydraulic check unit embodying this invention.

Figure 2 is a longitudinal sectional view taken 35 through the hydraulic check unit incorporated in the assemblage of Fig. 1.

Figure 3 is a sectional view taken on the plane III—III of Fig. 2.

Figure 4 is a reduced scale, top elevational view 40 of the assemblage of Fig. 1.

As shown on the drawings:

While this invention will be particularly described and illustrated in connection with the application of a hydraulic check unit to check the 45 movements of a picker stick of a loom, it will be obvious to those skilled in the art that such application is merely exemplary, and the hydraulic check unit embodying this invention is obviously adaptable to many other applications.

50 Referring to Figure 1, the numeral 10 indicates the rock shaft of a loom while the numeral 11 indicates a conventional picker stick. Picker stick 11 is supported for oscillating movements with respect to the rock shaft 10 by a linkage 55 which controls the movement of the picker stick

so that the top end of the stick traverses a substantially horizontal, straight line path. Such linkage, which is described and claimed in George H. Hufferd's copending application, Serial No. 37,951, filed July 9, 1948, now Patent No. 2,566,890, issued September 4, 1951, and assigned to the assignee of this application, may comprise a primary bracket 12, rigidly secured to the rock shaft 10, and secondary bracket 13 which is connected to primary bracket 12 by a pair of pivoted links 14 and 15. Links 14 and 15 may each constitute two identical parallel link elements or a single link, depending entirely upon the nature of their pivotal supports. The location of the pivot points of links 14 and 15, as well as the relative dimensions of such links are selected in the manner described in the above referred to copending application, so that the picker stick 11 can move only in a path which will result in the upper end of the stick moving along the lay (not shown) of the loom in a substantially horizontal, straight line path.

Thus, primary bracket 12 constitutes an integral casting having a split extension portion 12m defining a cylindrical recess to receive the end of rock shaft 10 and being clamped to rock shaft 10 by a bolt 12e and a key 12f which is drawn into clamping engagement with the rock shaft 10 by a nut 12g.

In addition, primary bracket 12 defines three spaced pivot bearings 12a, 12b and 12c respectively. Pivot bearing 12a is located in slightly depending relationship with respect to the rock shaft 10, and adjacent the end thereof, and provides pivotal support for one end of the link 15. Pivot bearing 12a is preferably of bifurcated construction and thus surrounds the end of link 15. A pin 16 pivotally connects link 15 and pivot bearing 12a, and link 16, if desired, may incorporate an eccentric portion (not shown) in the manner described in detail in the above referred to copending application so as to permit limited adjustment of the effective length of link 15 varying the angular position of the pivot pin 16.

Pivot bearing 12b on primary bracket 12 is also of bifurcated construction and is located directly above the end of rock shaft 10 to provide pivotal support for the cylinder element 21 of an hydraulic check unit 20 embodying this invention and to be described in more detail later.

Lastly, pivot bearing 12c is defined by a yoke-shaped portion 12d of primary bracket 12, and such pivot bearing is disposed in generally triangularly spaced relationship with respect to pivot bearings 12a and 12b and pivotally journals one end of the links 14.

The secondary bracket 13 is of generally reversed E-shaped configuration, and may be conveniently formed by a riveted assemblage of two half parts, as indicated by rivets 13e. The back side of the upright portion of bracket 13 is suitably apertured as indicated at 13d (Fig. 4) so as to conform to and snugly partially surround the bottom portion of the picker stick 11. Picker stick 11 is rigidly clamped in recess 13d by a plurality of U-shaped clamps 17 which are suitably threadably secured to secondary bracket 13 by bolts 17a.

Secondary bracket 13 likewise defines three pivot bearings which are respectively located in the ends of its arm portions. Thus a bifurcated pivot bearing 13a is formed in the end of the lowermost arm portion and pivotally journals the other end of link 15. A bifurcated pivot bearing 13b is mounted in the end of the top arm

portion and pivotally journals the end of the piston rod 26 of the hydraulic check unit 20. Lastly, a pivot bearing 13c is provided in the end of the intermediate arm of secondary bracket 13 and pivotally journals the other ends of links 14. All of the pivot bearings heretofore mentioned, except pivot bearing 12a, embody conventional pivot pins and grease fittings 9.

Conventional mechanism is provided for producing the required oscillating movement of the picker stick 11, such as a lug strap (not shown) which engages an intermediate portion of the picker stick 11. The lug strap is operated by conventional mechanism so as to periodically shift the picker stick 11 from its extreme outward position to its extreme inward position, and in so doing, accelerates the picker stick 11 so rapidly that the shuttle (not shown) which is in contact with the upper end of the picker stick 11, is violently thrown to the other side of the loom. After the shuttle is thrown, the inward movement of the picker stick 11 is checked by the hydraulic unit 20 in a manner to be described and the picker stick 11 is brought to rest at its extreme inward position. Thereupon, a torsion spring 40, operating between secondary bracket 13 and link 15 is effective to urge the picker stick 11 outwardly at least to an intermediate neutral position wherein a leaf spring stop portion 41a carried by an arm 41 pivotally secured to secondary bracket 13 by an eccentric pin 43, engages a fixed pin 44 transversely mounted in the primary bracket 12. At this point, the picker stick 11 is properly positioned to receive the initial contact by the shuttle when the shuttle is thrown back from the other side of the loom. The construction of the leaf spring stop 41 and the eccentric adjusting mechanism therefor is described in detail and claimed in George H. Hufferd copending application, Serial No. 37,952, filed July 9, 1948, now Patent No. 2,519,372, of August 22, 1950, and assigned to the assignee of this application, and reference should be had thereto for a more detailed description.

Upon the contact of the returning shuttle with the top end of the picker stick 11, the stick 11 is violently driven outwardly, and such outward movement must be checked by the hydraulic unit 20 to rapidly and smoothly bring the picker stick 11 to rest without producing a rebounding of the shuttle therefrom or permitting excessive forces to be developed in the picker stick 11 or any portion of its control linkage. Furthermore, the picker stick 11 must be brought to rest in substantially the same position each time so that the shuttle is properly positioned in the shuttle box.

From the foregoing discussion, some of the principal operating characteristics of the hydraulic check unit 20 have been indicated. Such unit must be of the double acting type and preferably provide a checking action only at each end of the opposite directions of movement of the picker stick 11. In addition, as is well known, the operating characteristics of the loom vary substantially with temperature and humidity conditions as well as with wear of various component parts thereof. As the result, it is essential that the checking action exerted by the hydraulic check unit 20 be conveniently manually adjustable, at least with respect to the effective checking action exerted upon the outward, or shuttle catching stroke of the picker stick 11, while the loom is operating, so that optimum conditions of checking, and hence uniformity of operation may be maintained. Furthermore, it is essential that the checking unit produce a

minimum resistance to movement of the picker stick 11 during the initial portions of its power or shuttle throwing stroke, which constitutes the movement of the picker stick from its extreme outward position toward its extreme inward position.

The foregoing characteristics are admirably supplied by an hydraulic check unit 20 embodying this invention. Referring particularly to Figures 2 and 3, the hydraulic check unit 20 is seen to comprise a cylinder casing 21 having a hollow bore 21a therein closed at one end and successively counterbored from the other end as indicated at 21b, 21c and 21d. The casing 21 at its closed end defines a pivot bearing 21e by which the unit is pivotally supported upon the pivot bearing 120 of the primary bracket 12.

A liner sleeve 23 is inserted in the first counterbore 21b of the casing bore 21a and is rotatably adjustable therein. Such adjustment may be effected in any convenient manner, for example, by a pinion 24 which is journaled in a generally radially extending aperture 21f provided adjacent the closed end of cylinder casing 21. The pinion 24 is preferably manually rotatable, such as by a flexible shaft 25 which is suitably co-rotatably secured to the pinion 24 by a coupling 25a. Gear teeth 23a are formed on the end face of liner sleeve 23 and mesh with pinion 24. Hence upon rotation of the flexible shaft 25 by a suitable control knob (not shown), which may be located on the machine in any convenient position for the operator, the angular position of the sleeve 23 and the cylinder casing may be varied.

A piston rod 26 is provided which is slidably journaled in a sleeve bearing insert 22a, which is in turn mounted in a central bore of a bearing support ring 22 which is snugly mounted in the largest counterbore 21d of casing 21 and retained therein by a snap ring 8. The inner end of piston rod 26 is threaded as indicated at 26a, and a piston 27 is adjustably positioned on such threaded end by a pair of opposed nuts 28. The outer end of piston rod 26 is provided with an integrally formed pivot bearing boss 26b by which the piston rod 26 is pivotally mounted to the uppermost pivot bearing 13b of the secondary bracket 13. Accordingly, the movements of the picker stick 11 relative to the primary bracket 12 will produce an axial reciprocation of the piston rod 26 with respect to the cylinder casing 21.

The piston 27 is of generally cup-shaped configuration and, while its bottom end face 27a is substantially perpendicular to the axis of the piston rod 26, the opposite face 27b is shaped so that at least a portion of the periphery of such face is generally helically inclined with respect to the piston rod axis. For example, the inclined face 27b may be formed by cutting the rim portion of the piston 27 at an acute angle to the axis of the piston.

The entire interior of the piston casing 21 is filled with a suitable hydraulic fluid in normal operation. In order to provide a controlled checking action upon the relative movements between the piston 27 and the liner sleeve 23, the liner sleeve 23 is provided with a plurality of axially spaced throttling apertures 29 and 30 respectively. Such apertures are, of course, in fluid communication by virtue of the fact that they are disposed in the counter-bored portion 21c of the cylinder casing 21 and hence substantially unimpeded fluid passage between the throttling apertures is provided exteriorly of the liner sleeve 23. It is therefore apparent

that any time the piston 27 is positioned intermediate the throttling apertures 29 and 30, fluid will be bypassed around the piston by flow through the throttling apertures 29 and 30 and around the exterior of liner sleeve 23.

The effective fluid passage areas of the throttling apertures 29 and 30 which are exposed in any particular position of piston 27 determines the rate of flow of fluid around the piston and hence, determines the effective checking action exerted upon the axial movements of the piston. Such throttling apertures are therefore complexly shaped in an axial direction to provide the desired checking characteristics required in each particular axial position of the piston 27. Thus the throttling aperture 29, which is effective to check the inward or power stroke of the picker stick 11 after the shuttle has been thrown, has a relatively short and narrow axial extension 29a, so that the movement of the piston 27 to the left as viewed in Figures 2 and 3 is very rapidly checked after the piston once begins to override the throttling aperture 29. In contrast, the throttling aperture 30, which effects the checking of the picker stick after it is contacted by the shuttle thrown from the other side of the loom, permits a much greater length of travel of the piston 27 and a more gradual increase of the fluid checking action. Thus the throttling aperture 30 is provided with a tapering axial extension 30a which reduces in effective cross sectional area as in the direction of travel of the piston 27 to the right as viewed in Figures 2 and 3.

The rate of decrease of effective fluid passage area of the throttling aperture extension 30a is, of course, proportioned according to well known design procedure to provide the desired degree of throttling at each successive axial position of the piston 27 as the piston rod 26 moves to the right as viewed in Figures 2 and 3, so that the piston 27, and hence the picker stick and shuttle will always be stopped at substantially the same position.

As was heretofore indicated, it is practically impossible to adjust the check unit for the picker stick of the loom to exactly provide the desired checking characteristics prior to assembling the unit in the loom and observation of the operation of the loom. This is particularly true with respect to the checking of the outward stroke of the picker stick, wherein much greater energy forces must be absorbed and yet the picker stick must be accurately brought to rest in a predetermined relationship with respect to the shuttle box.

The described construction permits a very accurate adjustment of the checking effects with respect to the axial position of the piston 27 during the outward movement of the piston rod 26, which corresponds to the outward movement of the picker stick. By rotating the sleeve 23 by the described manual adjusting mechanism, the effective angular position of the throttling aperture 30 with respect to the helically extending portion 27b of the face of the piston 27 is shifted, and, as a result, a variation is effected in the amount of checking action produced in any particular axial position of the piston 27, as it moves to the right as viewed in Figures 2 and 3. It is therefore apparent that the checking action may be accurately adjusted after the check unit is assembled to the loom and while the loom is operated, and hence variations in the operating

characteristics of the loom may be readily compensated for by adjustment of the rotational position of the sleeve 23 with respect to the piston 27.

To prevent fluid leakage from the cylinder casing 21 a sealing ring 31 is mounted in an annular groove provided in the periphery of the bearing support 22 and such link sealingly engages the cylindrical wall of the outermost counterbore 21d. To prevent fluid leakage along the shaft of the piston rod 26, a sealing unit 33 is mounted in surrounding relationship to such rod and disposed in a counterbore 22b formed in the outer end of the bearing support block 22. Such sealing unit may obviously comprise any one of several well known arrangements and will not therefore be described or illustrated in detail.

In the normal operation of those portions of the hydraulic check unit heretofore described, the fluid displaced by the axial movement of the piston will, of course, flow from one end to the other of the chamber defined by the liner sleeve 23 through the flow paths provided by the throttling apertures 29 and 30. When the hydraulic check unit is employed in applications where a small relatively slow movement of the piston rod 26 occurs, such bypass fluid flow will readily take place. However, when applied to checking the movements of a picker stick of the loom, or similar applications, the acceleration of the piston rod 26 is so rapid that an excess of fluid tends to be discharged through the throttling apertures 29 or 30 as the case may be, so that a substantial increase in fluid pressure in that portion of the check unit surrounding the liner sleeve 23 would be produced. This condition is particularly prevalent during the inward movement of the piston 27 which corresponds to the shuttle throwing stroke of the picker stick.

In addition, whether the check unit is employed in applications where rapid or slow movement of piston rod 26 occurs, it will be apparent that the volume of the cylinder chamber defined by liner sleeve 23 will be decreased each time piston rod 26 enters the chamber, therefore the hydraulic fluid will either be displaced or will undergo an increase in pressure.

Inasmuch as normal operating temperatures are in the vicinity of 150°, it will be further apparent that the hydraulic fluid will tend to expand following a period of sustained operation therefore, the hydraulic fluid will either be displaced or will undergo an increase in pressure.

If the pressure of the hydraulic medium were permitted to increase, fluid resistance would interfere with the travel of the piston 27 through the intermediate portions of the stroke. Therefore, this invention provides a second sleeve 34 which is concentrically mounted with respect to the liner sleeve 23 in the second counterbore 21c of the cylinder casing 21. The cylinder casing 21 is provided with an integral hollow protuberance 21k which defines a cylindrical reservoir chamber 21m. The protuberance 21k is so disposed with respect to the axis of the piston rod 26 that the axis of cylindrical reservoir chamber 21m is substantially vertical when the check unit 20 is assembled in the picker stick linkage, as shown in Figure 1. Reservoir chamber 21m is in fluid communication with substantially the entire external periphery of secondary sleeve 34 by the provision of an annular recess 21n in the intermediate portions of the second counterbore 21c of the cylinder casing 21.

Protuberance 21k is provided with an integral top wall 21p which in turn defines a centrally

disposed filling opening 21q. A closure plug 36 is threadably insertable in the end of filling opening 21q and, when the interior of the cylinder casing 21 is filled with sufficient fluid to completely fill the spaces between the sleeves 23 and 34 and to partially fill the reservoir chamber 21m, a trapped air space is then defined between the level of fluid in the reservoir chamber 21m and the closed top wall 21p. Such trapped air space is employed to permit ready increase in the volume of fluid contained in the reservoir chamber 23 whenever the hydraulic fluid is displaced from within the liner sleeve 23.

Fluid communication between the interior of secondary sleeve 34 and the reservoir chamber 21m is provided by an aperture 34a in the secondary sleeve 34 which is preferably located at a remote position with respect to the reservoir chamber 21m, such as in the bottom side of the secondary sleeve 34. Such location of the aperture 34a provides a relatively long flow path between the interior of liner sleeve 23 and the reservoir chamber 21m so as to substantially absorb all of the surging effects of the excess fluid pumped out of the liner sleeve 23. This damping of the surging tendencies of the fluid prevents the formations of air bubbles or frothing of the fluid in the reservoir chamber 21m and hence prevents air from being drawn into the liner sleeve 23 where it would substantially interfere with the checking action exerted upon the piston 27.

To bleed the interior of the liner sleeve 23 and the space between liner sleeve 23 and secondary sleeve 34 of any air that may have been drawn in during operation, a restricted area passage 34d is defined at one end of the sleeve 34 which communicates with a recess 21r milled into the outer counterbore 21d of the cylinder casing. Passage 34d also permits bleeding of air during the initial filling of the cylinder unit 20 with fluid. A fluid passage 21s communicates between recess 21r and reservoir chamber 21m. The recess 21r also communicates with an annular groove 21t provided in the outer counterbore 21d of the cylinder casing 21t which, in turn, is in communication through general radial holes 22c with the seal mounting chamber defined by counterbore 22b formed in the bearing support 22. Hence any fluid that leaks along the piston rod 26 through the bearing insert 22a will be returned to the cylinder portion of the check unit. It should be noted that radial holes 22c also serve to bleed to the reservoir chamber 21m any air which may pass in along piston rod 26 through sealing unit 33.

To provide a convenient indication of the proper level of fluid to which the check unit must be filled, the cylinder casing protuberance 21k is provided with a sleeve portion 21w surrounding the filling opening 21q and projecting into the interior of the reservoir chamber 21m. The extent of projection of the sleeve portion 21w is proportioned to correspond to the desired height of the trapped air space to be achieved within the reservoir chamber 21m when the check unit is assembled in the picker linkage and filled with fluid. Sufficient fluid is added to the interior of the check unit 20 so as to bring the fluid level up to the bottom face of the sleeve 21w and this level of fluid may be readily detected merely by observation through the fluid opening 21q. Hence, a very uniform trapped air space may be maintained within the check unit 20 throughout successive fluid filling operations and uniformity

of checking action upon the picker stick linkage is thereby assured.

It is therefore apparent that the described check unit provides an unusually simple yet effective arrangement for accommodating the hydraulic fluid displaced as a result of the acceleration of piston 21, the variations in the volume of the cylinder chamber or the variations in the volume of the hydraulic fluid. At the same time, surging of the displaced excess fluid is substantially eliminated so that no frothing of the trapped air is produced. The filling arrangement insures that a uniform trapped air space will be maintained within the check unit so as to conveniently indicate the proper filling level of fluid in the check unit. Obviously, the amount of fluid contained in the reservoir chamber 21m is readily variable as a function of the pressure of such fluid, the excess fluid being conveniently accommodated merely by compressing the air contained in the trapped air space at the top of such chamber.

It will, of course, be understood that various details of construction may be modified through a wide range without departing from the principles of this invention and it is, therefore, not the purpose to limit the patent granted hereon otherwise than necessitated by the scope of the appended claims.

We claim as our invention:

1. An hydraulic check comprising a hollow casing defining a primary chamber adapted to be filled with fluid, a first sleeve mounted in said chamber, a piston reciprocable in said first sleeve, said first sleeve having throttling apertures therein to bypass fluid around said piston at a limited rate to exert a predetermined checking action on the movements of said piston, a second sleeve surrounding said first sleeve and spaced therefrom, means on said casing defining a reservoir chamber communicating with the exterior of said second sleeve, at least a portion of said reservoir chamber being disposed at a higher gravitational level than said primary chamber, a fluid charge filling both said sleeves and part of said reservoir chamber, the uppermost part of said reservoir chamber defining a trapped air space, and said second sleeve being apertured at a region remote from said trapped air space to accommodate flow of excess fluid from said primary chamber into said reservoir chamber, whereby surging of said excess fluid flow is substantially eliminated.

2. An hydraulic checking unit comprising a hollow casing defining a primary chamber adapted to be filled with fluid, a first sleeve mounted in said chamber, a piston reciprocable in said first sleeve, said first sleeve having throttling apertures therein to bypass fluid around said piston at a limited rate to exert a predetermined checking action on the movements of said piston, a second sleeve surrounding said first sleeve and spaced therefrom, said casing being additionally recessed to define a reservoir chamber above said second sleeve and communicating with the exterior of said second sleeve, said second sleeve having an aperture in the lower side thereof providing a relatively long flow path from said throttling apertures to said reservoir chamber, and a fluid charge filling both said sleeves and a portion of said reservoir chamber.

3. The combination defined in claim 2 wherein the top portions of said reservoir chamber define a trapped air space, the top wall of said reservoir chamber having a depending sleeve

projecting into said reservoir chamber and defining a filling opening, the extent of projection of said sleeve into said reservoir chamber being proportioned to correspond to the desired height of the trapped air space, and closure means for said filling opening.

4. An hydraulic check unit comprising a hollow casing defining a cylindrical bore, a liner sleeve mounted in said bore and adapted to be filled with fluid, a piston axially reciprocable with said liner sleeve, at least a portion of one face of the piston having a periphery generally helically disposed relative to the sleeve axis, said sleeve having throttling apertures in the wall thereof permitting fluid flow around said piston and providing controlled resistance to axial movement of said piston, means for relatively angularly shifting said piston and said sleeve, thereby varying the axial location of said piston at which a predetermined resistance to movement of the piston is produced, a second sleeve surrounding said first sleeve and spaced therefrom, means on said casing defining a reservoir chamber communicating with the exterior of said second sleeve, at least a portion of said reservoir chamber being disposed at a higher gravitational level than said cylindrical bore, a fluid charge filling both said sleeves and part of said reservoir chamber, the uppermost part of said reservoir chamber defining a trapped air space, and said second sleeve being apertured at a region remote from said trapped air space to accommodate flow of excess fluid from said first sleeve into said reservoir chamber, whereby surging of such excess fluid flow is substantially eliminated.

5. An hydraulic check unit comprising a hollow casing defining a cylindrical bore adapted to be filled with fluid, a first sleeve rotatably mounted in said bore, a piston axially reciprocable in said first sleeve, at least a portion of one face of said piston being generally helically disposed relative to the sleeve axis, said first sleeve having throttling apertures in the wall thereof permitting fluid flow around said piston to provide a controlled resistance to axial movement of said piston, said first sleeve having gear teeth on one end thereof, a pinion journalled in said casing and meshing with said gear teeth, manually operable means for rotating said pinion, thereby angularly shifting said throttling recess relative to said helical portion of said piston face, a second sleeve surrounding said first sleeve and spaced therefrom, said casing being additionally recessed to define a reservoir chamber above said second sleeve and communicating with the exterior of said second sleeve, said second sleeve having an aperture in the lower side thereof providing a relatively long flow path from said throttling apertures to said reservoir chamber, and a fluid charge filling both said sleeves and a portion of said reservoir chamber.

6. A hydraulic unit for checking and controlling a shuttle loom comprising, in combination, a closed casing adapted for mounting on a portion of the loom and having one end thereof successively counterbored to define a series of stepped cylindrical walls, a rotatable sleeve in one of said counterbores, a truncated cylindrical piston axially reciprocable in said sleeve and having a driven connection with a relatively movable portion of the loom, means for sealing the piston end of the casing, said sleeve defining axially spaced complexly shaped apertures, and means for selectively rotating said

11

sleeve relative to said piston to vary the relative position of said apertures, thereby adjusting the checking characteristics of said unit, said casing further defining a hollow protuberance located generally at a normally upper portion of said unit and being in communication with the counterbore portions, whereby fluid displaced by said piston will be forced through said complexly shaped apertures and into said hollow protuberance.

7. A hydraulic unit for checking and controlling a shuttle loom comprising, in combination, a closed casing adapted for mounting on a portion of the loom and having one end thereof successively counterbored to define a series of stepped cylindrical walls, an adjustable rotatable sleeve in one of said counterbores, a truncated cylindrical piston axially reciprocable in said sleeve and having a driven connection with a relatively movable portion of the loom, means for sealing the piston end of the casing, said sleeve defining axially spaced complexly shaped apertures, means for selectively rotating said sleeve whereupon said apertures will be adjustably positioned relative to said piston to adjust the checking characteristics of said unit, said casing further defining a hollow protuberance located generally at a normally upper portion of said unit and being in communication with the counterbore portions, whereby fluid displaced by said piston will be forced through said complexly shaped apertures and into said hollow protuberance, and a second apertured sleeve in one of said counterbores surrounding said rotatable sleeve to lengthen the flow path presented to the displaced fluid between said apertures and said hollow protuberance.

8. A hydraulic unit for checking and controlling a shuttle loom comprising, in combination, a closed casing adapted for mounting on a portion of the loom and having one end thereof successively counterbored to define a series of stepped cylindrical walls, a sleeve in one of said counterbores, a piston axially reciprocable in said sleeve and having a driven connection with a relatively movable portion of the loom, means for sealing the piston end of the casing, said piston defining a peripheral face having variable axial dimensions, said sleeve defining axially spaced complexly shaped apertures, means for selectively varying the positioning of the spaced apertures and the face of the piston to adjust the checking characteristics of said unit, said casing further defining a hollow protuberance located generally at a normally upper portion of said unit and being in communication with the

counterbore portions, whereby fluid displaced by said piston will be forced through said complexly shaped apertures and into said hollow protuberance, and a second apertured sleeve in one of said counterbores surrounding said rotatable sleeve to lengthen the flow path presented to the displaced fluid between said apertures and said protuberance, said protuberance defining a depending sleeve formed on the top wall thereof and constituting a fluid filling opening for said hydraulic unit, said sleeve constructed to define a visually observable fluid level whereby a uniform air space may be maintained above the body of fluid in said unit in the upper portion of said hollow protuberance.

9. A hydraulic unit for checking and controlling a shuttle loom comprising, in combination, a casing adapted for mounting on a portion of the loom and having a hollow bore formed therein, a rotatable sleeve in said bore, a truncated cylindrical piston axially reciprocable in said sleeve and having a driven connection with a relatively movable portion of the loom, means for sealing the piston end of the bore, said sleeve defining axially spaced complexly shaped apertures, and means for selectively rotating said sleeve relative to said piston to vary the relative position of said apertures, thereby adjusting the checking characteristics of said unit, said casing further defining a hollow protuberance located generally at a normally upper portion of said unit and being in communication with the hollow bore to receive fluid displaced by said piston through said complexly shaped apertures.
